REVERSIBLE CONDIMENT CONTAINER

Richard A. Watson, Calgary, Alberta, Canada

Application August 28, 1958, Serial No. 757,870

8 Claims. (Cl. 222—142.2)

My invention relates to new and useful improvements in condiment dispensers, particularly dispensers adapted for use with pepper and salt.

It is well-known that it is extremely irritating to ask for and pass separate salt and pepper containers while dining, and furthermore they often become separated and misplaced.

It is known that double-ended containers are available, but unfortunately these suffer from the disadvantage of leaking occurring at one end if that particular end is facing downwardly.

I have overcome these disadvantages by combining the pepper and salt containers together, enabling them to be reversed easily and returned automatically, and furthermore, I have provided a sealing plate at the base thereof which seals off the end of the container which is facing downwardly so that no leakage can occur.

The principal object and essence of my invention is therefore, to provide a double-ended cylinder having containers at each end for salt and pepper, mounting same on a common spindle between a pair of supports which can be pivoted inwardly. By the provision of a pin and file groove, inward pressure of the side supports causes the device to rotate thus presenting the opposite end for use and at the same time the sealing plate is engaged and disengaged from the lower end thus preventing leakage.

The principal object and essence of my invention is, therefore, to provide a combination pepper and salt container in which the portion of the device which is downwardly does not leak when not in use.

A further object of my invention is to provide a device of the character herewithin described in which either the salt or pepper dispensers can readily be placed into position for use.

A yet further object of my invention is to provide a device of the character herewithin described which is extremely simple in construction, economical in manufacture and otherwise well suited for the purpose for which it is designed.

With the foregoing objects in view, and such other objects and advantages as will become apparent to those skilled in the art to which this invention relates as this specification proceeds, my invention consists essentially in the arrangement and construction of parts all as hereininafter more particularly described, reference being had to the accompanying drawings in which:

Figure 1 is a front elevation of my device.

Figure 2 is a side elevation of Figure 1.

Figure 3 is a view similar to Figure 1, but sectioned to show the interior thereof.

Figure 4 is a horizontal section along the lines 4—4 of Figure 2.

Figure 5 is an enlarged sectional view of one of the collars.

Figure 6 is a plan detail in part of the lower end of one side support pivoted connection.

2

Figure 7 is a fragmentary side elevation of the spindle showing the spiral grooves therein.

In the drawings like characters of reference indicate corresponding parts in the different figures.

5 Proceeding, therefore, to describe my invention in detail, reference should be made to the accompanying drawings in which it will be seen that I have provided a condiment container collectively designated 1 consisting of an elongated cylinder 2 having a container 3 at one end and a container 4 at the other end for containing condiments such as pepper 5 and salt 6, said containers having screwed end caps 7 for filling purposes, said end caps being apertured as at 8 for dispensing purposes.

The solid central portion 9 of the cylinder is provided 15 with a pivot pin or spindle 10 secured therein and extending upwardly upon each side thereof and the extended ends 11 of this spindle are provided with spiral threads or grooves 12 and enlarged ends 13, the purpose of which is hereinafter to be explained.

20 Side supports 14 are semi-cylindrical when viewed in plan, the lower ends 15 thereof being extended so that they meet together at a common pivot point 16 upon a cylindrical base plate 17. The lower ends being at right angles to the vertical support, they fit upon the base plate 25 as illustrated which maintains the two side supports in spaced and parallel relationship one with the other yet permits the other ends thereof to be moved together by finger pressure pivoting around the aforementioned pivot pin 16.

30 Collars 18 are situated around the ends 11 of the spindle and against the inner sides of the side supports 14, said collars having a pin 19 extending inwardly therefrom engageable with the aforementioned spiral grooves 12, and coiled springs 20 surround the ends 11 of the spindle and react between the sides of the cylinder and the collars normally maintaining the side supports in the vertical position as shown in the drawings.

The outer surfaces of the side supports may be knurled and these side supports are gripped between the thumb and forefinger of the user.

To dispense condiment from the end 5, the device is merely upended and shaken.

However, to dispense condiment from the end 4, the side supports are squeezed together thus causing the pins 45 to move inwardly and to rotate the spindle and cylinder so that the opposite end takes up the position of the end 3 shown in the drawing.

Release of this pressure permits the spring 20 to turn the side supports to the vertical position which at the 50 same time reverses the position of the cylinder.

In order to prevent leakage or spillage occurring from the end of the cylinder facing downwardly, I provide a bracket 21 secured to one of the side supports, said bracket extending inwardly and supporting an arcuately curved sealing plate 22 which is adapted to engage snugly the arcuately curved end caps 7 of the device. When in the position shown in the drawings, the arcuate sealing plate is relatively tightened against the end caps 7, but as soon as pressure is applied to the side supports in order to rotate the device, this end cap moves away slightly thus permitting the cylinder to rotate freely. Conversely, as soon as pressure is removed, the cylinder returns to the position shown in the drawings and the sealing plate clamps securely upon the arcuate end thus preventing leakage.

The spindle 10 is enclosed in a compressible tubular cover 23 where it projects between cylinder 2 and each side support 14, in order to prevent possible clogging by spilled condiments.

70 Since various modifications can be made in my invention as hereinabove described, and many apparently widely

different embodiments of same made within the spirit and scope of the claims without departing from such spirit and scope, it is intended that all matter contained in the accompanying specification shall be interpreted as illustrative only and not in a limiting sense.

What I claim as my invention is:

1. A condiment container comprising in combination a double-ended cylinder having a condiment dispensing container at each end thereof, a pivot pin secured to and extending at right angles through the centre of said cylinder and extending upon each side thereof, said pin having a spiral groove on the surface thereof at each extended end, a base plate, a pair of supports pivotally secured to said base and extending upwardly therefrom in spaced and parallel relationship, a pair of collars in the upper ends of said supports adapted to receive the ends of said pivot pins, pins in said collars extending inwardly and engaging said spiral threads so that movement of said supports together causes said spindle and said container to rotate.
2. The device according to claim 1 which includes at least one spring around said spindle reacting between the side of said cylinder and one of said supports and adapted to return said support to said spaced and parallel relationship.
3. The device according to claim 1 in which the ends of said cylinder are arcuately curved when viewed in side elevation, an arcuately curved sealing plate supported by one of said supports and adapted to cover and

enclose the dispensing end of said container adjacent the base of said device.

4. The device according to claim 2, in which the ends of said cylinder are arcuately curved when viewed in side elevation, an arcuately curved sealing plate supported by one of said supports and adapted to cover and enclose the dispensing end of said container adjacent the base of said device.

5. The device according to claim 1 in which said supports are semi-cylindrical, the lower ends of said supports extending inwardly to meet centrally upon said base at a common pivot point.

6. The device according to claim 2 in which said supports are semi-cylindrical, the lower ends of said supports extending inwardly to meet centrally upon said base at a common pivot point.

7. The device according to claim 3 in which said supports are semi-cylindrical, the lower ends of said supports extending inwardly to meet centrally upon said base at a common pivot point.

8. The device according to claim 4 in which said supports are semi-cylindrical, the lower ends of said supports extending inwardly to meet centrally upon said base at a common pivot point.
